UNITED STATES PATENT OFFICE.

CHARLIE SPETH, OF PALMYRA, NEBRASKA.

ROAD-GRADER.

1,339,866.

Specification of Letters Patent.

Patented May 11, 1920.

Application filed July 24, 1919. Serial No. 313,068.

To all whom it may concern:

Be it known that I, CHARLIE SPETH, a citizen of the United States, residing at Palmyra, in the county of Otoe, State of Nebraska, have invented certain new and useful Improvements in Road-Graders; and I do hereby declare the following to be a full, clear, and exact description of the invention, such as will enable others skilled in the art to which it appertains to make and use the same.

This invention relates to road graders and it has for its object to provide a structure of the rotary conveyer disk type wherein during the advance of the grader, the dirt may be discharged at any desired point of the periphery of the disk, within certain limits, thus to adjust the apparatus to road-ways of different widths and to the different specific conditions under which it is used.

A further object of the invention is to provide a grading machine embodying an extremely simple yet effective means for adjusting the depth of cut of the plow and also to provide a general frame structure that will be not only efficient but very cheap of manufacture and entirely durable.

Reference is had to the accompanying drawings forming a part of this application, wherein like characters designate corresponding parts throughout the several views, in which—

Figure 1 is a plan view of my improved road grader,

Fig. 2 is an edge view showing the position of the device during the initial use thereof,

Fig. 3 is an edge view at right angles to Fig. 2 showing the completed work, and

Fig. 4 is a cross section.

Referring to the drawings in detail, my improved road grader is shown as embodying a relatively large disk 10 preferably made up of a series of boards 11 crossed at right angles and suitably secured or nailed together so as to produce a rigid structure not likely to warp. This disk is provided with top and bottom reinforcing bands or rings 12 preferably in the form of an iron rim securely riveted to the boards, although it is to be understood that the disk may be constructed of any other desired material.

Disposed vertically through the axis of the disk is a shaft 13 to which is connected the free ends of the upper and lower forks of a beam 14, the outer end of which is re-

duced in thickness and has pivotally connected thereto a wheeled draft frame 15 which is turnable on the king bolt 16 so that the machine can be drawn over a desired course. The frame 15 is provided with the usual draft tongue 17.

Extending laterally from the lower portion of the beam 14 is an axle 18 at the outer end of which is journaled a wheel 19 which is disposed in contact with the under edge portion of the disk so that the disk will be supported to revolve thereon or to permit said wheel to revolve therebeneath as the animals are driven to encircle the disk. The axle 18 is braced to the beam 14 by a brace rod 20.

Arranged upon the beam 14 is a seat 21 for the driver and pivotally secured to the shaft 13 is a radially extending plow beam 22 carrying a single mold board plow 23 at its free end so as to extend beneath the disk with its concaved face disposed inwardly so as to excavate the dirt and throw the same upon the disk as the apparatus progresses or the plow is caused to revolve or travel around the disk. A brace 24 is arranged between the beam 14 and the free end of the plow beam 22.

A gage wheel 25 operates in advance of the plow and is journaled upon the laterally directed end 26 of a bell crank lever 27 pivotally mounted in bearings 28 on the plow beam 22, the other end of the lever constitutes a handle 29 which extends in convenient position above the draft beam 14 for manipulation by the occupant of the driver's seat. This handle is designed for engagement with a notched standard 30 so that the gage wheel may be raised or lowered to regulate the depth of action of the plow in the ground.

Also mounted on the shaft 13 pivotally, is a radial beam or arm 31 which carries at the rear side of its free end a scraping blade 32. This blade extends at an acute angle rearwardly from the beam 31 with its outer end projecting slightly beyond the periphery of the disk 10 while its other end extends inwardly of the disk. Thus as the apparatus advances, and the disk rotates by reason of its lower edge portion touching the ground, the dirt on the disk delivered to it by the plow, comes in contact with this scraper blade and by it is shoved off from the edge of the disk. It will of course be understood that as illustrated, the wheel 19 holds the

disk at an angle to the horizontal so that the opposite edge portion runs upon the ground to rotate the disk. It will be further understood that with the apparatus standing still, the team may be driven around the disk, which will serve to carry the scraper blade against the dirt on the disk instead of the dirt being carried by the disk against the blade.

With the apparatus advancing along a road, it is desired at times to discharge the dirt at different points transversely of the road. To accomplish this, it is only necessary to adjust the scraping blade angularly of the disk and this is accomplished through the medium of a connecting rod 33 which is pivoted to the beam 14 at the point of connection of the brace 24, and which connecting rod is provided with a longitudinal series of openings 34 at its rear end portion, to interchangeably receive a pin 35 that extends upwardly from the arm 31. By shifting the pin to one hole or another of the rod 33, it will of course be understood

that the arm 31 will be held at corresponding angles to the direction of advancement of the apparatus.

What is claimed is:

A road grader comprising an inclined rotatable disk, a forked draft beam straddling the disk and connected to the shaft, an axle connected with the beam at the under side of the disk and having a ground wheel upon which the higher side of the disk rests, a plow disposed to deliver dirt upon the disk and having a beam connected with said shaft, an adjustable gage wheel for the plow supported from the beam, an arm pivoted to the disk shaft and extending axially of the disk, and a blade carried by the arm in position to scrape dirt from the disk, the arm being adjustable angularly of the disk.

In testimony whereof I affix my signature in the presence of two witnesses:

CHARLIE SPETH.

Witnesses:

HARRY SLOSSON,
W. E. VAUGHAN.
